UNITED STATES PATENT OFFICE.

ROLF MEEG-LARSEN, OF DAMSGAARD, BERGEN, AND AAMUND BU, OF KINSARVIK, HARDANGER, NORWAY.

MOLD FOR CASTING CONCRETE POLES AND MASTS IN UPRIGHT POSITION.

Application filed January 2, 1925, Serial No. 246, and in Norway January 14, 1922.

Our invention relates to an improved mold for building concrete masts and poles in upright position.

Such masts and poles at present usually are cast in horizontal position either in a concrete casting plant or in the vicinity of the place of erection. When sufficiently hardened they are transported to the place of erection, and erected, but as such masts and poles are brittle, breakage often occurs. They are also very heavy and consequently the costs of transport and erection are considerable.

Masts or poles of great length or for great loads cannot be built in this way owing to their excessive weight, and such masts therefore have to be cast in upright position at the place of erection, but hitherto this has only been possible through the building up of a complicated scaffolding, such scaffolding involving large costs for mounting, dismantling and transport and also causing a great waste in lumber. This tends to increase unduly the costs of such masts or poles.

The object of our invention is to reduce such costs by using a method according to which is used a mold of sufficient rigidity to withstand the stresses caused by the casting process and the other stresses to which the poles are exposed while still in a soft or semisoft state, simultaneously providing, simple, but effective means for holding the mold in place in upright position, such means comprising a number of bracing wires or struts, fastened to the mold in suitable height above the base.

In the following we will describe our method with reference to the accompanying drawing, showing in side view a mast or pole of reinforced concrete under construction.

In casting a reinforced concrete pole according to our method we use a continuous mold of an interior cross section and form corresponding to the pole or mast to be cast, said mold having one of its sides composed of detachable wall sections or shutters.

In the executional form shown in the drawing is used a mold, for a pole of rectangular cross section. The two sides 1 of the mold consist of boards, nailed on to cross trees 2. These cross trees 2 are provided with holes for screw bolts 5. The third side 3 of the mold consists of boards 3, nailed to-

gether to form a continuous mold side wall which is placed between the above mentioned two sides 1 of the mold and are kept in place by aid of wedges 4 that are driven in between the boards 3 and the screw bolts 5 interconnecting the opposing two sides of the mold carrying the cross trees 2. The fourth side wall of the mold is built up of detachable sections or shutters 6, which are removed and again put in position as the casting process proceeds.

The side walls of the mold as well as the sections or shutters are tapered upwards so as to conform with the desired taper of the pole or mast.

When a pole or mast is to be cast in accordance with our method we first interconnect the two opposing mold sides 1 with the third side wall 3 of the mold by aid of the screw bolts 5 adjacent to it and wedges 4 driven between them and the said mold side 3 so as to clamp this mold side between the bolts and the edges of the two opposing mold sides 1, the three mold sides thus forming a trough-like structure. In this trough is loosely placed the reinforcing element 7, preferably in previously interconnected state. Thereupon the fourth mold side, consisting of separate sections or shutters 6 is fastened in place, likewise by aid of wedges 4 driven in between the adjacent screw bolts 5 and said sections. One or more of the said sections are, however, left open in order that the reinforcing element may be temporarily tied to the corresponding screw bolt 2, thereby holding it in place within the mold during the mold raising operation. In the drawing the uppermost section 6 is shown removed and the reinforcing element tied to the adjacent bolt 5 by aid of a wire 8.

At the base end of the mold the part of the element 7 destined for forming the reinforcing of the base block to be cast into the cavity 9 is left sticking out. Across this base cavity is laid a floor 10 having an opening corresponding to the cross section of the mold at the base.

After these preparations the mold with the element 7 fastened within it is raised on the floor 10, with its lower opening registering with the opening in the floor, and with the lower end of its reinforcing element depending into the base cavity 9, as shown in the drawing. The fastening of the mold in vertical position is effected by aid

of bracing stays or struts 11, the lower end of the mold with its cross pieces 1 fitting against the floor 10, so as to prevent the concrete from being squeezed out between the 5 base end of the mold and the floor. The floor or cover 10 may also be laid in place after the raising operation.

When the casting is to begin the lowermost of the sections or shutters 6 is removed 10 by knocking its wedges out, whereupon the casting material is filled in until the base cavity 9 is filled, whereupon this section is again put into its place and the next shutter is removed and casting material is filled in, 15 until the upper edge of the first named shutter is reached, and in this way we proceed until the mold is completely filled.

This casting operation takes place without the use of any scaffolding, the cross pieces 2 20 of the mold serving as steps for the casting operator. Separate steps may also be fastened to the mold, if necessary.

For transport of the casting materials there may suitably be fastened a bracket 12 25 to the top end of the mold, carrying a block or sheave 13, provided with a hoisting rope 14.

It will be understood that the scope of the invention is not limited to the particular 30 executional form illustrated and described but comprises the use of any form of mold arranged to be put together and hoisted into upright position and adapted to be subsequently filled with casting material by aid 35 of detachable mold sections or shutters. The

base may also be included in the mold, in which case the mold is raised with its base resting on the bottom of the base cavity. Or the base may be cast beforehand, the mold being raised on top of it, and its armature being interconnected with that within the mold before the beginning of the casting operation. 40

Instead of being made of wood as illustrated the mold parts may also be made of 45 iron, or other metal, and the fastening of the reinforcing element within the mold may be effected in any suitable way.

Claims:

1. A mold for casting concrete poles and 50 masts in upright position, comprising, side walls, cross members clamping the side walls together, clamping means interconnecting the cross members, one of the side walls being composed of a plurality of detachable 55 sections.

2. A mold for casting concrete poles and masts in upright position, comprising, side 60 walls, cross members clamping the side walls together, clamping means interconnecting the cross members, one of the side walls being composed of a plurality of detachable sections, the cross members being fastened to opposite side walls, the cross 65 members being formed to constitute steps.

In testimony that we claim the foregoing as our invention, we have signed our names.

ROLF MEEG-LARSEN.
AAMUND BU.
